UNITED STATES PATENT OFFICE.

JOHN COVINGTON TIDY, OF LONDON, ENGLAND.

DEVICE FOR CLEANING AND POLISHING KNIVES AND THE LIKE.

1,188,582.

Specification of Letters Patent. Patented June 27, 1916.

Application filed April 21, 1916. Serial No. 92,668.

To all whom it may concern:

Be it known that I, JOHN COVINGTON TIDY, a subject of His Majesty the King of Great Britain, and a resident of London, England, have invented certain new and useful Improvements in Devices for Cleaning and Polishing Knives and the like, of which the following is a specification.

This invention relates to improvements in devices for cleaning and polishing knives and the like and has for its object to provide a simple and inexpensive cleaning device by means of which knives can be readily cleaned.

15 The invention has reference to knife cleaners comprising a box like casing open at one end and provided with a hinged lid so that if a knife is reciprocated from the open end between a pad on the underside of the lid 20 and a similar pad within the box, the cleaning operation can be readily and expeditiously performed.

25 My present invention consists broadly in providing means whereby two operating apertures are provided, one for primary cleaning of very dirty knives and a second for final polishing or for use where the knives are not very dirty.

It has been usual to provide two cleaning 30 surfaces in a device having a book-like formation and consisting of three plates or slabs hinged together at one end; there are disadvantages connected with this type of apparatus, one being that the plates or slabs 35 have to be of considerably greater width than is absolutely necessary for the easy accommodation of the oscillating knife, for the reason that if there is nothing to constrain the knife to its cleaning position it 40 is liable to slip out at the sides; this is not only dangerous but also results in a waste of knife powder, or whatever medium is used; another disadvantage is that the grit or dirt is apt to fall from between the leaves 45 and so limits the use of the article to certain places where the distribution of dirt is unimportant; and besides the dirt and grit which escapes, the cleaning powder is liable to the same mishap which greatly deteriorates 50 from the economic efficiency of the article as a whole. In some cases it has been found necessary to provide a special tray for the article to catch such flying matter, but in practice this is not always efficient and is better dispensed with. The

means I provide in my invention for surmounting these difficulties comprise a removable member provided with polishing surfaces on both sides and adapted to be inserted in position so that one side co-operates with a polishing surface on the underside of the lid and the other co-operates with a polishing surface upon the bottom of the box. By this means damp pads— 60 which more rapidly and effectually remove bad stains—can be provided and after operation upon the damp pads a final polish 65 can be effected upon the final polishing pads.

In a device of this kind the box may be made comparatively narrow and so a great 70 saving of polishing powder is effected, and undue lateral movement of the knife, which is calculated to cut the cloth or other material of which the polishing surfaces are formed, is prevented. Further there is no 75 scattering of dirt or grit while the device is in operation and it may conveniently be used in any place and set aside until it is desired to empty out the collected dirt, when it is only necessary to remove the central 80 pad and shake the device over a dust bin or like receptacle.

It will be appreciated that both pads are subjected to the same pressure without 85 change of position.

In the accompanying drawings I have illustrated my invention, Figure 1 being a transverse section of the cleaner, and Fig. 2 a plan view thereof.

Referring to these drawings I provide a 90 box or casing 1 open at one end. The bottom of the box is provided with a pad 2 adapted to receive the polishing powder indicated at 3 and this pad can advantageously be kept a little damp. Resting upon this bottom pad I provide a removable board 4 provided with pads 5 and 6 one on each side. The pad 5 on the lower face co-operates with the fixed pad 2 on the bottom of the box and the pad 6 upon the upper face co-operates with a further pad 7 upon the underside of a hinged lid 8. This lid is preferably hinged as indicated at 9 at the end remote from the open end and in operation pressure is applied at or near its free 95 extremity which preferably has a raised portion or platform such as 10 to receive the hand of the operator. A projection 11 on the underside of the box provides a shoulder which may be firmly pressed against the 100 105 110

edge of a bench, table, or the like, when the device is in use.

When it is desired to clean a knife, the article is first inserted between the damp bottom pad and the coöperating pad immediately above it and the knife is reciprocated longitudinally of the box. The knife is then withdrawn from this position and is inserted between the polishing pad upon 10 the underside of the lid and that immediately beneath it whereby a final polish is applied. To clean the hilts of the knives and for cleaning forks and the like, the lid is turned about its hinge so as to expose its 15 polishing pad which can thus be used after the fashion of a knife board, the hinge being so arranged as to permit the folding back of the lid without straining the hinge, and if desirable the lid may be provided upon 20 its outer face with a block upon which the pressure can be applied during the main cleaning and polishing operations and which will serve as a support when the lid is laid

open to enable its padded underside to be used as a knife board of ordinary form. 25

Having thus described my invention, I claim:

A knife cleaning device comprising in combination a relatively long and relatively narrow box having two sides, a bottom and 30 an end rigidly fastened together; a top for said box hinged to said end and having a cleaning pad fixed to the normally under surface thereof; a pad fixed to the top surface of said bottom; a removable member 35 normally in said box having pads on both top and bottom thereof; and a raised portion on said top for applying pressure thereon.

In testimony whereof I affix my signature in presence of two witnesses.

JOHN COVINGTON TIDY.

Witnesses:
